UNITED STATES PATENT OFFICE.

ROBERT P. GARSED, OF NORRISTOWN, PENNSYLVANIA.

PNEUMATIC BELL-RINGING.

SPECIFICATION forming part of Letters Patent No. 268,882, dated December 12, 1882.

Application filed September 16, 1882. (No model.)

To all whom it may concern:

Be it known that I, ROBERT P. GARSED, a citizen of the United States, and a resident of Norristown, in the county of Montgomery and State of Pennsylvania, have invented a new and useful Improvement in Pneumatic Door-Bells or Alarms, of which the following is a specification.

The object of my invention is to furnish a pneumatic door-bell in which one pull of the bell-knob will cause the bell to ring a number of times; and I accomplish this object by the mechanism illustrated in the accompanying drawings, in which—

15 Figure 1 is a side view of my invention; Fig. 2, an enlarged side view of the pump and plunger; Fig. 3, a sectional view of the same; Fig. 4, a back view of the same; Fig. 5, a side view of the winding-spring; Fig. 6, a side view of the hammer and its operating-wheel, and Fig. 20 7 a side view of the collapsible bellows.

25 My air-pump A is represented in the drawings as a hollow rubber ball or sphere; but it may in practice have any other suitable shape, and is operated by a plunger, B. The pump A is situated in a metallic hemisphere, C, which is bolted securely to the inside of the door-frame, and it has an orifice, D, in its end, through which the compressed air passes in 30 order to operate my mechanism. The plunger is situated upon a frame-work, F, to which the bell-pull is attached, and this frame-work in the drawings is represented as being attached to a plate O, to which the bell-pull is fastened; 35 but if more convenient the guide-rods F may be twisted or soldered together to form an eye. The guide-rods F pass through slots in the rim or flange of the hemispherical cup C, and may be adjusted without detaching the plunger B, and 40 they are surrounded with spiral springs S, whose office is to assist in returning the plunger to its first position. Attached to the inner side of the flange of the hemispherical cup C, and at a suitable distance from and partly surrounding the guides, are fenders R, whose office is to keep the rubber pump from rubbing 45 against the rods F and springs S.

In the center of the plunger, and directly opposite the orifice D in the pump, a pipe, E, is 50 placed, through which the compressed air passes to a bellows, G, and, in order to allow

the plunger B to operate, a part, P, of this pipe is flexible or telescopic.

On top of the bellows G is a staple, H, between the legs of which a shaft, I, passes, upon one end of which is a toothed wheel, K, and upon the other a spring, M. The teeth of the wheel K engage with and operate the escapement L, upon which the striking-hammer of the bell is placed. The spring M has one end 55 securely fastened to the shaft I, and the other is secured to some convenient fixed place.

From the top of the staple H a cord or band, N, is suspended, which passes around and is secured to the shaft I. 60

The operation of the device is as follows: The bell-pull being drawn out, the plunger B is forced into the rubber sphere A, compressing the air therein, which passes through the orifice D and pipe E to the bellows G, raising 70 this bellows and the staple on its top and unwinding the band or tape N, which passes around the shaft I. The unwinding of this band causes the shaft I to be rapidly revolved, and with it the toothed wheel K, the teeth of 75 which engage with the escapement L, and cause the hammer to give the bell a number of rapid strokes. Instead of the toothed wheel and arm, there may be a number of hammers radiating from and attached directly to the 80 shaft I by means of flexible arms, and the rotation of the shaft would cause these hammers to strike the bell successively. When the shaft is revolved, in order to operate the striking mechanism, the spring M is wound up, and 85 when the air in the bellows G escapes the spring unwinds itself and revolves the shaft in the opposite direction, and winds up the tape N, and the device is again in a condition to be 90 operated.

It will be seen that the coil-spring N, by attachment to the shaft I, will collapse bellows G through the medium of a rack upon said bellows engaging with a pinion upon said shaft.

Having thus described my invention, I claim 95 and desire to secure by Letters Patent—

1. The combination, in a door-bell pump, of the perforate flexible sphere A, supported by the metal holder C, and with operating-plunger B, said plunger being attached to a pull, 100 and having an orifice in its center for the passage of air, and attachment to the pipe E through

the flexible or telescopic tubing P, and said flexible or telescopic tubing P, the whole adapted for ringing a bell, substantially as shown and described.

5. 2. As a means for operating a door-bell, and in combination with a device for pneumatically operating the bellows G, the bellows carrying a staple, H, and the band N, one end of which is attached to said staple, and the other wound 10 around the shaft I to revolve said shaft and to operate the hammer, substantially as shown and described.

3. As a means for collapsing the bellows G, and adapted to be wound up by the expansion 15 of said bellows, the spring M, one end of which is attached to the shaft I and the other to some fixed point, in combination with the tape N and staple H, or their equivalents, all arranged and operating substantially as shown 20 and described.

4. In a pump composed of the holder C, covering A, and plunger B, the latter attached to rods connected to a bell-pull and passing through a flange on said holder, the combination, with said rods and guide-flange, (the latter 25 adapted to receive the bearing of the springs,) the springs S, surrounding said rods, and the fenders R, fastened to the guide-flange, the springs adapted to return the plunger to its position when not actuated by the bell-pull, 30 and the fenders to prevent said springs or rods from rubbing against the rubber sphere, the whole operating substantially as shown and described, as and for the purposes set forth.

R. P. Garsed.
